NEWTON H. FORINGER, OF NEW CUMBERLAND, WEST VIRGINIA.

PIPE-CUTTER.

1,242,931.

Specification of Letters Patent. Patented Oct. 16, 1917.

Application filed August 10, 1916. Serial No. 114,232.

To all whom it may concern:

Be it known that I, NEWTON H. FORINGER, a citizen of the United States, residing at New Cumberland, in the county of Hancock 5 and State of West Virginia, have invented certain new and useful Improvements in Pipe-Cutters, of which the following is a specification.

This invention relates to pipe cutters, and 10 more particularly to a pipe cutter having a closed main cutter frame and an adjustable cutting element mounted therein.

One of the main objects of the invention is to provide a cutter of the character stated 15 having a cutting disk which may be adjusted within the cutter frame and which is securely braced against lateral displacement. A further object is to provide a cutter of simple construction and operation, which 20 may be tightly secured about the pipe to be cut. Further objects will appear from the detailed description.

In the drawings:—

Figure 1 is a top plan view of the invention, 25

Fig. 2 is a horizontal sectional view taken through the cutter frame near the top thereof,

Fig. 3 is a section on line 3—3 of Fig. 1, 30 and

Fig. 4 is a fragmentary detail sectional view showing the latch for operatively connecting the handle to the cutter frame.

The main cutter frame is composed of an 35 approximately semi-circular side plate 1 and upper and lower plates 2 and 3, respectively, secured thereto. The upper and lower plates project inwardly to form an annular channel in which is rotatably mounted a plurality of 40 anti-friction rollers 4. These rollers project slightly beyond the inner edges of the plates 2 and 3 so as to press against the periphery of the pipe being cut when the cutter is in operative position. At one end the main 45 cutter frame is provided with an integral outwardly tapering nipple 5. An internally threaded sleeve 6 fits loosely through this nipple and is provided, at its inner end, with spaced arms 7. A U-frame 8 has the 50 ends of its cross bar 9 reduced to form gudgeons which are pivotally mounted through the top and bottom plates 2 and 3 of the main cutter frame. By this means the U-frame is pivotally mounted at its outer 55 end. The arms of this U-frame have their inner ends provided with alined apertures

to receive a pivot pin 10. This pivot pin also passes through apertures through the inner ends of the arms 7 of sleeve 6. By this means the inner end of the sleeve and 60 the inner end of the U-frame are pivotally connected. A disk cutter 11 of suitable construction is mounted between the arms 7 of the sleeve and is provided, at each side, with an integral laterally extending spacing collar 12. This secures the cutter disk within 65 the arm in proper operative position while permitting free rotation of the same about the pin 10. An adjusting screw 13 is threaded into the sleeve 6 and has its outer 70 end reduced and passed through the cross bar 14 of a stirrup, the arms 15 of which are formed at their inner ends with integral laterally projecting gudgeons 16 which are loosely mounted in U-members 17 projecting 75 from the outer end of the nipple 5. This permits a rocking movement of the stirrup. The outer portion of the screw 13, beyond the bar 14 of the stirrup, is squared to fit 80 a corresponding aperture at the center of an operating lever 18 mounted about the same and secured in position by a nut 19 threaded on to the outer end of the screw. The screw 13 is further provided with an integral annular shoulder 20 between which 85 and the inner face of the bar 14 is interposed a washer 21. This effectually prevents longitudinal movement of the screw through the stirrup while permitting free rotation thereof. By rotating the screw, 90 the U-frame 8 may be adjusted about its pivotal axis so as to move the cutter disk 11 toward or away from the center of the main cutter frame, as desired. During this movement the stirrup rocks on the gudgeons 95 16 so as to readily adjust itself to the angular variations of the sleeve 6.

A ring 22 is secured to the upper edge of the cutter frame 1. This ring is provided with a segmental portion 22^a pivotally secured thereto at one end. The other end of this segmental portion is bored to slidably receive a locking bolt 23, the outer end of which is adapted to engage a bore in the body of the ring. The portion 22^a is further provided with a recess adapted to receive a block 24 secured on the bolt 23 and a compression spring 25 confined between the block and the inner end of the recess and mounted about the bolt. By this means the 105 bolt is held in position to secure the member 22^a in closed position so as to complete the 110

circular outline of the ring. An approximately three-quarter circular collar 26 is interposed between the upper edge of the main cutter frame and the lower face of ring 22 and is of somewhat less diameter than the ring so as to permit the ring to project slightly beyond the collar.

A cover is mounted loosely about the upper portion of the main cutter frame and is adapted to be connected thereto so as to rotate the same by means to be described. This cover comprises a top plate 27 of approximately the same shape as the upper and lower plates 2 and 3 of the main cutter frame but extending somewhat beyond the same. A flange member or collar 28 is secured to the under face of plate 27 and extends somewhat below the ring 22. An inwardly projecting annular collar 29 is secured to the flange member 28 near its lower end. This collar fits snugly about the collar 26 so as to project slightly inward beneath the ring 22. By this means the cover is mounted about the ring so as to be rotatable thereon but secured against outward movement relatively thereto.

The flange ring or member 28 is provided with an integral radially projecting arm 30 which is centrally bored to slidably receive the stem 31 of a latch head 32. The inner portion of this member is enlarged to form a chamber 33 which receives the expansion spring 34 mounted about the stem 31 and confined between the head 32 and the outer end of the chamber. The latch 32 is adapted to engage the teeth 35 formed integral with and projecting radially from the ring 22.

By this means, when the cover is rotated in one direction the cutter frame will be rotated also, while, due to the bevel of the inner end of the head 32 in one direction, the cover may be freely rotated in the other direction.

The sleeve 30 is provided, at its outer end, with a V-shaped recess 36. This recess is adapted to receive a V-shaped member 37 secured on the outer end of the stem 31 of the latch. By pulling this member outward and turning it at right angles to its normal position, the latch head will be held in inoperative position, thus permitting free rotation of the cover in either direction. The arm 30 is secured in a rectangular socket 38 formed integral with an operating handle 39. By means of this handle rotary motion may be imparted to the main cutter frame in any desired direction.

By moving the bolt 23 into inoperative position, the section 22^a of the ring 22 may be swung outward about its pivotal axis providing an opening through the ring so that the main cutter frame and the parts mounted thereon may be fitted about the pipe to be cut. When the pipe is within the frame 65 the section 22^a is moved into closed position

and locked in this position by the bolt 23. This provides an entirely closed frame which effectually eliminates all possibility of the pipe slipping out of the cutter. When the cutter has been adjusted as described, 70 the cutter disk 11 is moved inward by means of the lever 18 and screw 13 so as to be brought into cutting engagement with the pipe, after which the main cutter frame is rotated by means of the handle 39. During 75 the cutting operation the U-frame 8 serves to hold the cutter disk rigidly in position and to prevent lateral displacement of the same. This U-frame is subjected to tension only and this tension is exerted longitudinally of the frame, as a result of which this member can be made of relatively light construction. The sleeve 6 is subjected to longitudinal pressure only, and can also, for this reason be made of comparatively light 80 construction. By this arrangement of the bracing and adjusting means for the cutter disk, the disk is held rigidly in operative position and there is no danger of the bracing members becoming broken or distorted 85 due to the fact that the tension and pressure to which they are subjected is exerted upon lines extending longitudinally of the members.

There may be slight changes made in the 95 construction and arrangement of the different parts of my invention without departing from the field and scope of the same, and I intend to include all such variations in this application, as fall within the appended 100 claims, in which a preferred form only of my invention is disclosed.

What I claim, is:—

1. In a pipe cutter of the character described, the combination of a main cutter frame, a U-frame pivotally mounted therein, a rotary cutter carried by the U-frame, a sleeve pivotally connected to the U-frame and to the cutter frame, and means for adjusting the sleeve longitudinally. 110

2. In a pipe cutter of the character described, the combination of a main cutter frame, a U-frame pivotally mounted therein, a rotary cutter carried by the U-frame, a stirrup loosely mounted on the cutter frame, an internally threaded sleeve pivotally connected at its inner end to the U-frame, and an adjusting screw threaded into said sleeve and having its outer end loosely secured through the stirrup. 120

3. In a pipe cutter of the character described, the combination of a main cutter frame of approximately semi-circular shape open at one side, a U-frame pivotally mounted at its outer end in the cutter frame, 125 a cutter rotatably mounted in the inner end of the U-frame, an internally threaded sleeve pivotally connected at its inner end to the inner end of the U-frame, a stirrup rockably mounted on the cutter frame, an adjusting 130

screw threaded into said sleeve and having its outer end loosely secured through the stirrup, and means mounted on the cutter frame for operating the same.

- 5 4. In pipe cutters, a main cutter frame, a U-frame pivotally mounted therein at its outer end, a cutter carried by the U-frame at the inner end thereof, an outwardly extending sleeve pivotally connected at its 10 inner end to the said U-frame, a stirrup pivotally mounted on the cutter frame, said stirrup straddling the outer end of said sleeve and being in alinement therewith whereby all strain will be imparted to said 15 sleeve and stirrup longitudinally of the same during the cutting operation, and means carried by the stirrup and engaging with the sleeve for adjusting said sleeve longitudinally.
- 20 5. In pipe cutters, a main cutter frame, a U-frame pivotally mounted therein at its outer end, a rotary cutter carried by the U-frame at the inner end thereof, an internally threaded sleeve pivotally connected at its 25 inner end to the inner end of the U-frame, the axis of the pivotal connection of the sleeve being coincident with the axis of said

rotary cutter, a stirrup having the inner ends of its arms pivotally secured to the cutter frame, and an adjusting screw mounted 30 through the top bar of said stirrup for rotation in either direction and secured against longitudinal movement, said screw being threaded into the sleeve so as to adjust the same longitudinally when the screw is rotated.

6. In pipe cutters, a main cutter frame, a U-frame mounted therein at its outer end, a cutter carried by the U-frame, and means mounted on the cutter frame and connected 40 to the U-frame for adjusting the U-frame in either direction about its pivotal axis, the means for adjusting the U-frame and the U-frame being so relatively disposed that all strain will be transmitted to the U-frame and the adjusting means therefor along lines 45 extending longitudinally of these elements during the cutting operation.

In testimony whereof I affix my signature in presence of two witnesses.

NEWTON H. FORINGER.
